D. W. SUTHERLAND, JR.

ACIDITY TEST MACHINE

Filed May 1, 1924

Patented Jan. 26, 1926.

1,570,717

UNITED STATES PATENT OFFICE.

DONALD W. SUTHERLAND, JR., OF SIOUX FALLS, SOUTH DAKOTA.

ACIDITY-TEST MACHINE.

Application filed May 1, 1924. Serial No. 710,306.

To all whom it may concern:

Be it known that I, DONALD W. SUTHERLAND, Jr., a citizen of the United States, residing at Sioux Falls, in the county of Minnehaha and State of South Dakota, have invented certain new and useful Improvements in Acidity-Test Machines, of which the following is a specification.

This invention relates to certain new and useful improvements in acidity test machines and pertains more particularly to a machine for testing the acidity of cream and milk.

The primary object of the invention is to provide a machine of this type which enables testing in an easy and quick manner and to further provide a machine which is of simple, compact and economical construction.

A further object of the invention is to provide means for enabling the container for the cream or milk to be easily and quickly removed and accurately repositioned for further use, and to also provide novel means for holding the movable parts of the machine in a stationary predetermined position while the machine is out of operation or during removal of the liquid container and replacement thereof.

The invention has still further and other objects which will be later set forth and of themselves manifested in the course of the following description.

In the drawings:—

Figure 1, is a side elevation of the invention, and

Figure 2, is a top plan view thereof.

In proceeding in accordance with the present invention, a base plate 1 is employed which may be provided with depending feet 2. A vertical scale or plate 2' provided with two spaced series of graduations 3 and 4 is fixed to one end of the base plate, while the opposite end thereof is provided with a substantially J-shaped guide 3 that extends along the rear side and laterally of the base plate. A cup-like container 5 for reception of the milk or cream to be tested is freely received on the base and in the curved end or leg 6 of the J-shaped guide.

A lever 7 is pivoted intermediate its ends on a pin 8, the latter being supported by vertical members 9 rigidly secured to the base plate 1. Pin 8 has tapered ends received in nuts 8' carried by the vertical members 9. The forward end of the lever is curved at

10 and forms a support for an indicator 11, the latter being formed of a horizontal arm having pointed or arrow shaped ends 12. The indicator 11 is fixed central of its ends 12 to the curved end 10 of the lever, and operates in the space between the two series of graduations 3 and 4, so that the ends 12 lie opposite to the respective series of graduations. The opposite end of the lever is formed with an upwardly extending arm 13, the latter curving downwardly at 14 and carrying a float 15 on its free end. The float 15 operates in the cup 5, while the guide end 6 is positioned relative to the float so that when the cup is engaged with the guide end as depicted in Figures 1 and 2 of the drawings, the float will be accurately positioned in the center of the cup.

One of the bearings 9 is formed with an extension to which is pivoted a latching arm 15', the latter having one end engageable beneath the rear end of the lever while its opposite end is twisted to form a horizontal finger grip 17. A catch 18 is pivoted at 19 to the base plate and is engageable with the finger grip to hold the lever and float in the dotted line position depicted in Figure 1 of the drawings. A coil spring 21 tensions the catch to hold same in latching position.

The two scales are graduated for "sweet" and "sour" readings and the graduations are inclined so as to be in register with the various positions of the indicator arm during movement of the lever about its pivot.

In operation, in the instance of sweet cream, or milk 17.6 cubic centimeters are placed in the cup and in the instance of sour cream or milk 9.0 cubic centimeters. In the case of sweet milk or cream three or four drops of a 10% solution of phenolphthalein in ethyl alcohol are added and then a neutralizing solution N/44 NaOH, until a slight pinkish color is noted. The cup is now engaged with the guide, and the catch released, whereupon the float is lowered and the reading taken at the "sweet" scale. In the case of sour cream or milk, the same operation occurs, the acidity reading appearing on the "sour" scale in cubic centimeters.

What is claimed is:

1. In an acidity testing machine, a base, a vertical scale plate on the base having spaced vertical series of "sweet" and "sour" graduations, a lever pivoted between its ends to the base, a horizontal pointer on one end of

the lever operating in the space between the two series of graduations, a substantially J-shaped guide on the base plate adjacent to the opposite end of the lever, a liquid holding cup freely movable on the base and in the guide, the said opposite end of the lever extending upwardly and being curved downwardly, and a float on said curved end of the lever receivable in the cup.

5 2. In an acidity testing machine, a base, a vertical scale plate on the base having spaced vertical series of "sweet" and "sour" graduations, a lever pivoted between its ends to the base, a horizontal pointer on one end of the lever operating in the space between the

10 two series of graduations, a substantially J-shaped guide on the base plate adjacent

the opposite end of the lever, a liquid holding cup freely movable on the base and in the guide, the said opposite end of the lever extending upwardly and being curved downwardly, and a float on said curved end of the lever receivable in the cup.

25 3. In an acidity testing machine, a base, a vertical scale plate on the base, a lever pivoted between its ends to the base and having a pointer on one end cooperating with the scale plate, a cup on the base, a float on the other end of the lever receivable in the cup, a latching arm pivoted to the base plate and engageable at one end beneath the lever to hold the float upwardly above the cup to allow the latter to be moved out of register with the float, and a catch engageable with the opposite end of the arm to hold the latter in operative position.

30 4. In testimony whereof I affix my signature.
DONALD W. SUTHERLAND, JR.
